UNITED STATES PATENT OFFICE.

IRA LINWOOD STANGER, OF MERCHANTVILLE, NEW JERSEY.

ELECTRICAL SWITCHING DEVICE.

Application filed June 15, 1921. Serial No. 477,698.

To all whom it may concern:

Be it known that I, IRA L. STANGER, a citizen of the United States, and a resident of Merchantville, in the county of Camden and State of New Jersey, have invented a new and Improved Electrical Switching Device, of which the following is a full, clear, and exact description.

This invention relates to an electrical switching device, and has particular reference to a combined switch or cut-out and fuse block in which the live parts are substantially entirely enclosed so that the danger of persons operating the switch coming in contact with the live parts is reduced to a minimum.

Another object of the invention resides in the provision of means whereby the live parts above mentioned are substantially enclosed regardless of whether the switch is open or closed or in any position.

A further object resides in the provision of means whereby the fuses mounted in connection with this switch may be refilled and easily examined.

A still further object resides in the provision of means whereby in closing the switch the electrical circuit is not made until the lid or cover is substantially entirely in place, so that if a fuse is blown no danger results, and in opening the switch the parts are separated before the cover or lid is moved any great distance, so that any arc formed by opening the switch will not result in injury to the person operating it.

Another object resides in the particular construction and arrangement of parts which are hereinafter described and claimed and shown in the accompanying drawings.

The invention is shown in the drawings, of which—

Figure 1 is a plan view of the switch;

Figure 2 is a longitudinal section taken on the line 2—2 of Figure 1;

Figure 3 is a transverse section taken on the line 3—3 of Figure 1;

Figure 4 is a transverse section of the lid or cover taken on the line 4—4 of Figure 1;

Figure 5 is a perspective view of the device;

Figures 6 and 7 are longitudinal sections taken through the cover, base and body portions, respectively of the switching device when used as a cut-out; and

Figures 8 and 9 are sectional views re-

spectively taken on the lines 8—8 and 9—9 of Figures 6 and 7.

As shown in the drawings, the preferred form of my invention comprises, as shown in Figs. 1 to 4 inclusive, a base portion 1 in the form of a block or slab of any suitable insulating material. On the upper surface of this base portion are provided a plurality of recesses, such as 2, in which switch terminal clips, such as 3, are located. These clips are of any suitable well-known type and provided with the usual binding posts 4. Holes or apertures, such as 5, may be formed in the base portion to receive wires leading to the binding posts 4.

On top of the base portion 1 there is adapted to be placed a body portion 6 of any suitable insulating material. This body portion is provided with a plurality of recesses 7 so disposed as to align themselves over the recesses 2 when the body portion is in position on the base portion. Suitably formed slots 8 extend from the recesses 7 upwardly through the body portion to form a passage for other members of the switch to make contact with the clips 3. As seen in Fig. 2, there is a transverse wall 9 formed on each side of the switch between adjacent chambers in which the clips 3 are located so that each clip is disposed in a separate compartment or chamber by itself and access can be had thereto during the normal use of the switch only through the slots 8. It will also be seen that the body portion is provided with a curved wall 9 which divides the body portion in half longitudinally.

These downwardly extending curved walls are adapted to bear against a longitudinally projecting rib 10 on the base portion 1. Hinged to the body portion 6 is a cover portion 11 of any suitable insulating material, and within this cover or lid portion is disposed a plurality of switch knife blades 12. These are connected suitably to the lid portion and are provided with binding screws, such as 13. Apertures 14 extend through the lid to the underside of the knife blades 12 for testing purposes. A fuse, such as 15, may extend between pairs of binding posts in the usual manner. The lid or cover 11 is provided with a longitudinally extending wall 16 which is adapted to extend downwardly between the walls 9 on the body portion and engage with the rib 10 when the cover is in the closed position.

Figures 6 and 7 are longitudinal sections taken through the cover, base and body portions, respectively of the switching device when used as a cut-out; and

Figures 8 and 9 are sectional views re-

This additional wall divides or acts as a barrier between the pairs of switch blades 12 on opposite sides of the cover to provide an additional surety against injury to the 5 operator when using the switch. This wall 16 also acts as a barrier between fuses. Furthermore, the fact that the curved sloping walls 9 converge toward each other causes the wall 16 as it comes into the body 10 portion 6 to be properly guided into position. A transverse rib 17 at one end of the body portion 6 is adapted to engage with the corresponding groove 18 in the cover and further secure an alignment of the 15 parts. The body portion 6 is suitably held on to the base portion 1 by any suitable means, such as retaining screws 19. The ribs or walls 16' extending in opposite directions from the dividing wall 16 also 20 facilitate the enclosure of the fuses to prevent spreading of the flames therefrom when they are burned out.

A view of Fig. 1 will clearly indicate that when the body portion 6 is in place on the 25 base 1, the only possible way in which access may be had to each of the terminal clips 3 is through the slots 8, and a consideration of the proportions of the clips 3 with respect to the knife blades 12 indicate clearly that 30 before these parts come into electrical contact the cover, whether hinged or not, is substantially closed before this contact is made. If at that time a fuse should blow, therefore, the danger of fire from the flame 35 of the explosion or from the spark being formed when the switch is being opened, is substantially eliminated. Suitable circuit wires, such as 20, may be inserted through the apertures 5 above mentioned to connect 40 the proper parts to the circuit. The cover is also provided with ribs 21 extending longitudinally thereof which are adapted to lie against the edges 22 extending longitudinally along the upper portion of the body 45 portion adjacent the slots 8. These ribs also are adapted to prevent the fuses from slipping into the space which is occupied by the upper portion of the body adjacent the slots 8 when the cover is disposed on the body 50 portion. These edges by their interengagement tend to provide a very rigid contact device which when closed is held properly and rigidly in assembled position.

In Figs. 6 to 9, inclusive, I show a similar 55 form of switch, which may be used as a cut-out, in which the cover is not hinged to the body portion. In this case, as shown in

Fig. 7, I provide, as above mentioned, separate chambers 23 in which each one of the terminal clips 24 are located and to which 60 access can be had only through the slots 25. The body portion 26 is held on the base portion 27 by means of screws 28. The cover portion 29 is provided with knife blades 30 and binding screws 31 between which fuses 65 32 may be suitably disposed. The cover is provided with a dividing wall 33 and with longitudinally extending spacing ribs 34 adapted to engage with the upper edge 35 of the body portion 26. 70

Referring back to Fig. 2, it will be observed that the slots 8 are somewhat curved, as at 9, to permit the proper entry of the 75 blades 12 thereinto when the cover 11 is hinged on the body portion 6. 75

This switch, therefore, it will be observed, is made in two parts, one part being formed of the base and pockets or body portion which is disposed rather substantially 80 around the live contact, and the other part being composed of the face or cover containing the switch blade and fuses. This whole device is used as a box switch. The insulating parts of the switch may be molded, if desired, although any suitable insulating 85 material can be used. The switch, therefore, can be constructed so that it is not necessary to place it in a box or under cover in order to prevent the operator from coming in contact with the live parts. 90

What I claim is:

A switching device comprising a base portion, a body portion adapted to be disposed on said base portion and having formed therein two sets of separately 95 spaced chambers, a switching element in each of said chambers, said body portion having relatively long narrow slots therein leading to each of said chambers, the body portion formed with a longitudinally extending recess or passage between each set of chambers, a cover adapted to co-operate with the body portion, switching elements on the cover adapted to extend through the slots in the body portion to co-operate with the switching elements in the chambers, and a dividing wall disposed on the cover between the switching elements thereon and adapted to extend into the longitudinally extending groove or recess in the body portion to electrically and mechanically separate the 100 two halves of the body portion. 105

IRVING LINWOOD STANGER.
